UNITED STATES PATENT OFFICE.

GEORGE FRANK LADD, OF FORBES, NORTH DAKOTA.

DEVICE FOR USE IN SORTING AND DELIVERING MAIL.

Application filed May 11, 1926. Serial No. 108,399.

This invention relates to improvements in devices for use in sorting and delivering mail and while it may be employed by both city and rural mail carriers, it is one of 5 the objects of the invention to provide a device of this class which will be especially useful in the delivery of rural mail.

Another object of the invention is to provide a device of the class referred to which 10 may be conveniently employed first in the sorting of the mail in the post office in accordance with the order in which the mail is to be delivered to residences or places of business and which may, after the sorting of 15 the mail, be conveniently employed by the carrier in delivering the mail without any likelihood of confusion such as would result from a disarrangement of the sorted mail.

Another object of the invention is to provide 20 a device for use in sorting and delivering mail embodying a plurality of pockets into which mail for delivery to different residences and places of business is deposited as it is sorted and which device will be flexible to the extent that a considerable volume 25 of mail may be deposited in one or more pockets if the adjacent pockets are not filled to capacity, the arrangement being such that the bottoms of the pockets are displaceable 30 and the pockets are so arranged one above another that the bottom of each pocket will constitute, in effect, the top of the pocket beneath it, so that the desirable result referred to may be obtained.

Another object of the invention is to provide 35 a novel construction and arrangement of the pockets such as to provide for collapsing of the entire device to occupy minimum space after all of the sorted mail has 40 been deposited in the pockets thereof.

Another object of the invention is to provide 45 a device of the class referred to which will be extremely simple in construction and possess a maximum capacity and which, when not in use, may be collapsed to very compact form.

Another object of the invention is to so construct the device that it may be suspended above a bench or other support in a 50 post office while mail is being sorted and

which may be conveniently carried and likewise suspended within an automobile or other vehicle where the device is to be employed in making rural deliveries.

In the accompanying drawings:

Figure 1 is a perspective view of the device embodying the invention, supported in a suspended position for the sorting of mail, the view illustrating also the supporting means which likewise constitutes a part of 60 the invention.

Figure 2 is a vertical transverse sectional view in detail through the upper portion of the device.

Figure 3 is a vertical front to rear sectional view taken substantially on the line 3-3 of Figure 2, looking in the direction indicated by the arrows.

Figure 4 is a vertical transverse sectional view through a slightly modified form of 70 the device, the view illustrating the device supported in suspended position.

Figure 5 is a vertical front to rear sectional view through the upper portion of the modified structure shown in Figure 4.

Figure 6 is a plan view of one of the pockets of the modified structure spread out and before being arranged and secured within the body of the structure.

The invention comprises a flexible case 80 which is indicated in general by the numeral 1 and the side walls 2 and rear wall 3 of which are preferably formed of a single piece of canvas, oilcloth, or any other material of a flexible nature found suitable 85 for the purpose. The case further includes a sheet metal top 4 and a sheet metal bottom 5, and the upper and lower edges of the side walls 2 and rear wall 3 are preferably hemmed and folded over to respectively overlap the side and rear marginal portions of the top 4 and underlie the corresponding marginal portions of the bottom 5, the hems being secured by rivets or other suitable securing elements 6, to the said top and bottom.

At this point it will be evident that the case as a whole is collapsible inasmuch as all of its walls except its top and bottom are flexible. In order that the case may be suspended and likewise in order 100

that the same may be carried about in a convenient manner, a combined suspension and hand strap 7 is secured at its ends by rivets or other suitable securing elements 8 to the opposite side marginal portions of the top 4 substantially midway between the front and rear edges thereof, the said fastening elements passing also preferably through the hems at the upper margins of 10 the side walls 2 of the case. The front marginal portions of the side walls 2 are preferably hemmed as indicated by the numeral 9, so as to strengthen the open front of the case.

The invention contemplates the provision, 15 within the case, of a plurality of pockets arranged one above another in a vertical series, as clearly shown in the several figures of the drawings, and these pockets likewise are flexible to an extent which will now be made 20 apparent. The pockets are indicated in general by the numeral 10, and each of the pockets includes in its construction, a rectangular wire frame indicated in general by the numeral 11 and comprising side members 12 and front and rear end members 13 and 14. The bottom 15 of each pocket comprises a sheet of canvas or other suitable flexible material which is stretched at its marginal portions over the respective members 30 of the frame 11 and provided with hems 16 accommodating the said members of the frame, as best shown in Figures 2 and 3 of the drawings. Each pocket further comprises side walls 17 and a rear end wall 18, these walls being of canvas or other material of a flexible nature found suitable for the purpose and being preferably formed from a single piece of such material having its lower marginal portion extended 40 beneath the hems of the bottom sheet 15 at both the sides and the rear end of the said bottom and united thereto by the same stitches which establish the said hems. The upper margins of the side walls 17 and the 45 upper margin of the rear end wall 18 of each pocket are overturned and united by stitching as at 19 and 20 respectively, along horizontal lines, to the sidewalls 2 and rear end wall 3 of the case, and, preferably, the line 50 of attachment of the upper edges of the side and rear end walls of each pocket is located in a plane slightly above the plane of the bottom of the pocket next above, and likewise the frames 11 are preferably of dimensions 55 slightly less than the interior dimensions of the case, so that the bottom of each pocket will depend a short distance within and in spaced relation to the open top of the pocket next beneath it, as clearly shown in 60 Figures 2 and 3 of the drawings. The peculiar arrangement of the pockets with relation to one another holds true except that the top 4 of the case constitutes the top of the uppermost pocket while the spaces between 65 the lowermost pocket and the bottom

5 of the case constitutes, in fact, the lowermost pocket or receptacle for mail matter.

It will be evident that when the case is suspended as for example by the engagement of its handle 7 with a hook or other supporting means, as shown in Figure 1, and which means will be presently fully described, its side walls and rear wall will be straight or flat and perpendicular and the pockets will be suspended in full open position and semi-nested, as shown in the several figures of the drawings, the weight of the frames 11 constituting the bottoms of the pockets being positioned to render the side walls 17 and rear end walls 18 substantially taut. Therefore, when the case is suspended in this manner, mail may be introduced into the different pockets until all of the mail intended for introduction into the device has been sorted. To facilitate sorting of the mail, each pocket has associated with it a tag holder which will now be described. The tag holders for the pockets are indicated in general by the numeral 21 and each is preferably formed from a suitably shaped sheet metal blank and comprises a back plate 22 having a rearwardly extending flange 23 at its upper edge which is disposed in overlapping relation with respect to the forward edge of the bottom of the respective pocket and secured thereto by rivets or other suitable fastening elements 24, which pierce the sheet comprising the bottom 15 immediately rearwardly of the front member 13 of the respective frame 11. In forming the tag holders, the plate 22 at the juncture of its flange 23 or, in other words, at each upper corner, is formed with incisions and overturned to provide lugs 25 projecting downwardly in advance of the respective plate 22, and the lower marginal portion of each plate is turned upwardly upon itself, as indicated by the numeral 26, so that a card or slip of any sheet material of proper dimensions may be fitted into the holder with its lower edge engaging behind the flange 26 and its upper corners engaging behind the retaining lugs 25. Such card or slip will bear the name of the head of the household, for example, of a particular residence, or the name of the proprietor of a business place, or the name of the business place, on the carrier's route, and it will be preferable, of course, to arrange the cards or slips, which are indicated by the numeral 27, in the order in which the different residences and places of business will be reached by the carrier in traveling over his route. One of the tag holders will be mounted upon the forward edge portion of the top 4 and, of course, associated with the uppermost one of the pockets, and the tag holder which is supported upon the forward edge portion of the bottom of each pocket will, of course, relate to the pocket next beneath it. So far 70 75 80 85 90 95 100 105 110 115 120 125 130

as the invention is concerned, any other suitable identifying arrangement may be provided for the several pockets.

In the use of the device embodying the invention, one, or any number thereof, is suspended with its open front presented toward the one who is to sort the mail, and the pieces of mail are inserted into the proper pockets. The pockets have a uniform capacity, generally speaking, or, in other words, each pocket has its side and its rear end walls of the same height as any other one of the pockets. However, due to the peculiar construction and arrangement of the pockets within the case, the invention presents this advantage, namely, that if, in the sorting of the mail, the quantity of mail introduced into any one pocket is such that it extends from the bottom of the said pocket to the bottom of the pocket next above it, more mail may still be introduced inasmuch as the walls of the pockets are flexible and, therefore, the bottom of the last mentioned pocket may be elevated to a greater or less extent, as shown for example in dotted lines in Figure 2 of the drawings, and this holds true for each pocket except, of course, the uppermost pocket and, therefore, it may frequently occur that in any one of the devices, several of the pockets will be filled with mail matter occupying a greater space than the normal capacity of the pocket and inasmuch as the bottoms of all of the pockets are upwardly displaceable through the flexibility of their walls and the capability of the walls of collapsing as the bottoms of the pockets are elevated, it will seldom occur that any difficulty will be found in introducing into any one of the pockets all of the mail due for delivery to the recipient identified by the tag in the tag holder associated with the respective pocket. Therefore, the device may be said to have a maximum possible capacity and consequently presents a decided advantage over devices in which the pockets are more or less in the nature of non-flexible or non-expansile compartments having a limited capacity.

After all of the mail to be delivered has been sorted or distributed to the pockets, the case is removed from its suspension means and collapsed or permitted to collapse, to a more or less compact form, depending upon the quantity of mail matter introduced into the pockets thereof, and in order that the sorted mail matter may be securely retained within the pockets until the time of delivery, a strap 28 is fitted through loops 29 near the bottom of the case and upon the outer faces of the side walls 2 thereof and through other loops 30 similarly arranged near the top of the case, and this strap therefore extends about the case and, when drawn taut, may be so held through the medium of any ordinary type of buckle indicated by

the numeral 31. Preferably the strap is located a greater or less distance forwardly of a plane midway between the back and the open front of the case, so that the front portion of the case, in its collapsed condition, is constricted to a greater degree than the rear portion of the case and, therefore, the case is more restricted near the open forward ends of the pockets to better retain in place the pieces of mail matter which are arranged within the said pockets.

A convenient supporting means for the device during the period of sorting the mail is clearly illustrated in Figure 1 of the drawings, and the same comprises two base members or feet 32 which are secured in any suitable manner upon a bench or shelf 33, and standards 34 are mounted at their lower ends in or upon the base members 32 and at their upper ends fit into sockets 35 provided at the ends of a cross piece 36 which extends between the said upper ends of the standards and may be of any desired length, depending upon the number of the devices which are to be suspended therefrom. In the embodiment shown in Figure 1 of the drawings, the supporting structure is arranged to support a single one of the devices, and the standards 34 are spaced apart a distance to accommodate the device without lateral binding thereof. A suspension hook 37 is carried by the cross piece 36 and the suspension or hand strap 7 is engaged with this hook. Likewise, in the arrangement shown, the bottom of the case engages between the opposing sides of the base members 32, which members are arranged in parallelism to each other, and consequently there is no likelihood of lateral swinging of the device while mail matter is being inserted into the pockets. Of course, where several of the devices are to be supported, they will be arranged side by side and the cross piece 36 will be longer and provided with a corresponding number of the hooks 37, the uprights or standards 34 being likewise spaced apart a distance substantially equal to the requisite length of the cross piece as also the base members 32.

After the sorting of the mail matter, the devices are, as before stated, removed from the supporting or suspension hooks and collapsed and constricted by tightening the straps 28, and the strap 7 then serves as a handle by which the device may be carried to the vehicle employed by the postman. At such time, the straps 7 constitute a convenient means whereby the several devices may be suspended within the automobile or other vehicle beneath the top thereof and thus be protected from the elements as well as preventing soiling of the mail matter which might occur if the devices were merely deposited upon the floor of the vehicle body.

Figures 4, 5 and 6 of the drawings, illustrate a somewhat modified and likewise simplified construction of the pockets of the holder and, as clearly shown in Figure 6, 5 each of these pockets comprises a rectangular frame 38 which is preferably of wire and corresponds to the frame 11 of the pockets 10 in the previously described embodiment of the invention, the said frame comprising 10 side members 39, a front end member 40, and a rear end member 41. The pocket, in this embodiment, is formed from a single integral sheet of cloth material such for example as canvas, and this sheet is of rectangular contour and of somewhat greater dimensions than the frame 38. Opposite marginal portions of the sheet are folded in upon one face of the sheet to provide relatively broad hems 42, the folds embracing 20 the front and rear members of the frame, as clearly shown in Figures 5 and 6 of the drawings, and lines of stitching 43 being run through the hems close to the folds and consequently along and close to the inner sides of the said end members of the frame, and these lines of stitching being extended about the entire length of the front and rear marginal portions of the sheet of material. The marginal portions constituting the hems 42 30 have their edges hemmed and united by lines of stitching 44 to the body of the sheet so that a material reenforcement is provided at the front and rear ends of each pocket. The frame 38 is disposed equi-distantly from 35 the opposite side margins of the sheet comprising the pockets and lines of stitching 45 are run through the hems 42 at opposite sides of and close to the side members 39 of the frame so as to maintain the frame 40 and the pocket sheet in proper position with respect to each other. This arrangement of the frame leaves side portions 46 which, in fact, constitute the sides of the pocket and these sides are reenforced at their front and 45 rear ends inasmuch as the hems 42, as stated, extend throughout the entire length of the front and rear marginal portions of the sheet. The lateral margins of the sheet are hemmed, as indicated by the numeral 47, 50 and these hemmed edges are united by lines of stitching 48 to the side walls 49 of the case, which case, in this and in every other respect, corresponds to the case 1 of the previously described embodiment of the invention. It will be noted that in the modified 55 form of the invention, the entire pocket comprises the single sheet of material and the frame arranged and united as described and that the pocket is open at both its front and rear ends. However, the fact that each pocket is open at its rear end is not of material consequence inasmuch as the said ends of the pockets are disposed relatively close to the back of the case which, in the figures

illustrating the modification, is indicated by 65 the numeral 50.

Having thus described the invention, what I claim is:

1. In a device for use in sorting and delivering mail, a case having flexible side and rear walls adapting it to be collapsed, the case being open at its front, and a series of pockets within the case comprising bottom, side and rear walls, the side and rear walls of the pockets being flexible and thereby 75 adapted to be collapsed and being attached at their upper portions to the respective walls of the case, the pockets of the series being semi-nested with relation to one another whereby the bottom of one pocket may 80 constitute a displaceable top for the pocket next beneath it.

2. In a device for use in sorting and delivering mail, a case having an open front and relatively non-flexible top and bottom, 85 the case further comprising flexible side and rear walls adapting it to be collapsed, and a series of pockets within the case arranged one above another and having relatively non-flexible bottoms and flexible side and 90 rear walls, the said side and rear walls being connected at their upper portions to and suspended freely from the corresponding side and rear walls of the case.

3. In a device for use in sorting and delivering mail, a case having flexible side walls adapting it to be collapsed, and a series of collapsible semi-nested pockets within the case and each having a bottom and flexible 100 walls extending upwardly from the bottom and having their upper edge portions connected with the flexible walls thereof.

4. In a device for use in sorting and delivering mail, a case having flexible side and rear walls adapting it to be collapsed, the case being open at its front, and a series of pockets within the case arranged one above another and each comprising walls of flexible material united at their upper portions to the corresponding walls of the case, each pocket further including a non-flexible bottom extending between its walls and of dimensions less than the interior dimensions 110 of the case, the lower portion of one pocket depending freely within the upper portion 115 of the pocket next beneath it, whereby the pockets are freely collapsible with the case and whereby the bottoms of the pockets are freely upwardly displaceable.

5. In a device for use in sorting and delivering mail, a case having flexible side and rear walls adapting it to be collapsed, and a series of pockets arranged one above another within the case and each pocket comprising flexible walls attached at their upper 125 marginal portions to the corresponding walls of the case and suspended therefrom, each pocket further including a bottom comprising

ing a frame and a sheet of material stretched within the frame and connected at its marginal portions therewith and to the lower marginal portions of the walls of the pocket.

5 6. In a device of the character described, a case open at its front, and a series of pockets arranged one above another in the case, each pocket comprising a flexible body, and a bottom frame disposed upon said body,

the front and rear portions of the body 10 being folded over end portions of the frame and secured and the side portions of the body being extended upwardly and attached to side walls of the casing to suspend the pocket therein and permit upward displacement of its bottom. 15

In testimony whereof I affix my signature.
GEORGE FRANK LADD. [L.S.]
